UNITED STATES PATENT OFFICE

JUSTUS B. KINNEY, OF JAMAICA PLAIN, BOSTON, MASSACHUSETTS, ASSIGNOR TO
KINNEY MANUFACTURING COMPANY, OF BOSTON, MASSACHUSETTS

APPARATUS FOR MIXING OIL AND AIR

Application filed November 18, 1927. Serial No. 234,178.

This invention relates to means for mixing oil and air and is particularly adapted to provide the proper mixture of these elements preparatory to ejecting the mixture into an oil burner.

The object of the invention is to provide a simple but effective apparatus including an oil tank from which oil may be pumped and mixed with air under compression, all surplus oil not required in the mixture being returned to said tank.

This object is attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings:

Figure 1 represents a diagram of an apparatus embodying the principles of the present invention.

Figure 2 represents a vertical section of the oil pump and air compressor used in said apparatus, the cutting plane being on line 2, 2, on Fig. 5.

Figure 3 represents a vertical section of the same, the cutting plane being on line 3, 3, on Fig. 5.

Figure 4 represents a partial horizontal section of the same on line 4, 4, on Fig. 2, and

Figure 5 represents a horizontal section of the same on line 5, 5, on Fig. 2.

Similar characters indicate like parts throughout the several figures of the drawings.

In the drawings 10 is a tank adapted to contain oil suitable for use in oil burners.

From the lower end of said tank extends a delivery pipe 11 leading to the inlet 12 of a pump casing 13, this casing having an oil discharge pipe 14 leading therefrom through

which surplus oil may be returned to said tank 10.

The pipe 14 has a relief valve 15 therein of any well known construction which will open under a predetermined pressure and permit the flow of oil into the tank 10.

Within the casing 13 are two chambers 16, 17 and extending through these chambers are two parallel shafts 18, 19, the shaft 18 being rotated from any suitable source of power and the shaft 19 being driven thereby through the medium of pinion 20 secured to the driving shaft and the gear 21 meshing therewith and secured to shaft 19.

The pinion 20 and gear 21 are disposed within the chamber 17 and the gear 21 rotates in the direction of arrow *a*, on Figs. 2 and 3.

The ends of the teeth of the intermeshing gears 20, 21 contact with concentric portions of the wall of said chamber 17 so that any oil admitted to said chamber 17 through inlet 12 on the inlet side of said gears will be carried by said teeth to the opposite side of said gears where it may be discharged in predetermined quantities through a passage 22 in the wall or partition 22* between the chambers 16, 17.

The flow of oil through this passage 22 is regulated by a needle valve 23 threaded to the casing 13 and provided with an actuating handle 24 outside of said casing.

On the discharge side of the gears 20, 21 is an oil outlet 25 which communicates with the pipe 14 through which all oil not passing into chamber 16 may return to the tank 10 thus keeping up a continuous circulation of oil within the chamber 16 and keyed to shaft 19 is an eccentric 26 surrounded by an annular piston 27, one point of the periphery of which is always in contact with the cylindrical wall of said chamber.

The piston 27 is provided with a radial blade 28 extending through the diametrical slot 29 of an oscillating pin 30 mounted in cylindrical bearings 31 within said casing 13.

The blade 28 is provided with a passage 32 extending inwardly from its outer end and having at its inner end a lateral passage 33, the inner end of which is a short dis-

tance from the periphery of the annular piston 27.

As the eccentric 26 revolves in the direction of arrow α on Fig. 3, during a portion of its cycle when the passages 32, 33 are closed, the piston 27 will compress the air admitted to said chamber 16 and as soon as the lateral passage 33 is uncovered this compressed air will be discharged through the passages 32, 33 and into the pipe 34 through which it will be forced into the oil burner.

The air is admitted to the casing 13 through the pipe 35 which communicates with a compartment 36 which in turn communicates with the chamber 16. Likewise the air discharged from the passage 32 will pass through an outlet compartment 34 before entering the discharge pipe 34.

The passage 22 from chamber 17 also communicates with this compartment 34 so that any oil entering said compartment 34 through said passage 22 will be discharged in a path perpendicular to the path of the air delivered from passage 32.

This will cause the air and oil to be thoroughly mixed before the mixture enters the discharge pipe 34 so that the air compressed within said chamber and being discharged through the pipe 34 will be thoroughly impregnated with oil.

For the proper operation of the oil burner the amounts of oil and air must be properly proportioned, and this can be accomplished by adjusting the needle valve 23.

The central portion 13^a of the casing 13 has formed therein the chamber 16, the compartment 36 and the cylindrical bearing 31 and has formed thereon bosses into which the ends of pipes 34, 35 are threaded.

Against the front face of this central portion 13^a is positioned the partition wall 22 having the passage 22 therein.

Against the outerface of this wall 22^a is positioned an end plate 13^b and against the rear face of the central portion 13^a is positioned an end plate 13^c.

The plates 13^b and 13^c are provided with long closed bosses 37 to receive and form bearings for the opposite ends of the shaft 19 and the end plate 13^b is provided with a similar boss 38 to receive and form a bearing for one end of the shaft 18.

These end plates 13^b, 13^c are secured to the central portion 13^a of casing 13 by means of bolts 39.

The rear end plate 13^c is provided with a stuffing box 40 through which the rear end of the driving shaft 18 extends, the projecting end being connected with any means for imparting rotation thereto.

It will be obvious, therefore, that there can be no leakage of either oil or air when once admitted to the chambers and compartments within said casing and when delivered to the oil burner the mixture of oil

and air may be in the exact proportions desired and under constant pressure.

Should under certain conditions any change in the proportions of the mixture of oil and air be desired, such change may be quickly made by adjusting the needle valve 23 without stopping the operation of the oil pump and air compressor.

The tank 10 may be buried as the action of the oil pump will be to create a suction and draw the oil from the tank and this same pump will mix the oil thus obtained with air while the compressor will supply to the burner a required mixture of oil and air always under pressure.

Manifestly it is a great advantage to combine in a single casing both a means for pumping oil and a means for compressing air, driving both mechanisms from the same driving shaft, and furthermore, providing a means whereby the oil and air may be thoroughly mixed in any desired proportions before discharge from the casing.

Another advantage is the provision of means whereby any surplus oil not required in the mixture may be returned to the oil tank without loss.

It is believed that the operation and many advantages of the apparatus will be fully understood without further description.

Having thus described my invention, I claim—

1. The combination of a casing having a piston chamber therein; two shafts extending through said casing, one a driving shaft; an eccentric keyed to the other shaft within said piston chamber; an annular piston surrounding said eccentric with a portion of its periphery contacting with the cylindrical wall of said chamber; an oscillating slotted member; a blade on said piston extending through the slot of said member and having an air discharge passage therethrough; an air inlet to said piston chamber; a gear chamber in said casing parallel to said piston chamber; a gear therein secured to the piston shaft; a pinion in said gear chamber secured to the driving shaft; means for admitting oil to said gear chamber on one side of said intermeshing gears; a passage from said gear chamber on the discharge side of said intermeshing gears and leading directly to the outlet of said piston chamber; means for controlling the flow of oil through said passage; and means for returning surplus oil to the source of oil supply.

2. The combination of a casing having two parallel chambers therein separated by a partition having a passage therethrough directly connecting said chambers; two parallel shafts revolvably mounted in said casing; intermeshing gears on said shafts in one chamber, said chamber being provided with an oil inlet on the opposite side of said gears from said passage; air compressing

- means in the other chamber actuated by the rotation of the driven shaft; means for controlling the flow of oil through said passage; and means for returning surplus oil to the source of oil supply. 5
3. The combination of a casing having a piston chamber therein and an outlet compartment communicating therewith; means within said piston chamber for compressing air; an air inlet to said chamber; a gear chamber in said casing; an oil inlet to said gear chamber; a passage from said gear chamber leading directly to said outlet compartment; a needle valve for said passage; and gears in said gear chamber adapted to pump oil through said passage into said outlet compartment. 10
4. The combination of a casing having a piston chamber therein and an outlet compartment communicating therewith; means within said piston chamber for compressing air; an air inlet to said piston chamber; a gear chamber in said casing; an oil inlet to said gear chamber; a passage from said gear chamber to said outlet compartment; a needle valve for said passage; gears in said gear chamber adapted to pump oil through said passage to mix with the air passing through said outlet compartment; a discharge pipe from said gear chamber; and a relief valve in said discharge pipe. 15
5. The combination of a casing having a piston chamber therein and an outlet compartment communicating therewith; means within said chamber for compressing air; an air inlet to said piston chamber; a gear chamber in said piston casing; an oil inlet to said gear chamber; a passage from said gear chamber leading directly to said outlet compartment; a needle valve for said passage; two shafts extending through said casing, one a driving shaft; a piston forming part of the air compressing means and actuated by the other shaft; a gear secured to the piston shaft; and a pinion meshing therewith secured to the driving shaft. 20
6. The combination of a casing having a piston chamber therein and an outlet compartment communicating therewith; two shafts extending through said casing, one a driving shaft; an eccentric keyed to the other shaft within said piston chamber; an annular piston surrounding said eccentric with a portion of its periphery contacting with the cylindrical wall of said chamber; an oscillating slotted member; a blade on said piston extending through the slot of said member and having an air discharge passage therethrough; an air inlet to said piston chamber; a gear chamber in said casing parallel to said piston chamber; a gear therein secured to the piston shaft; a pinion in said gear chamber secured to the driving shaft; an oil inlet to said gear chamber on one side of said intermeshing gears; a passage from said gear chamber on the opposite side of said intermeshing gears and leading to the air outlet compartment; and means for controlling the flow of oil through said passage. 25
7. The combination of a casing having two parallel chambers therein separated by a partition having a passage therethrough directly connecting said chambers; two parallel shafts revolvably mounted in said casing; intermeshing gears on said shafts in one chamber said chamber being provided with an oil inlet on the opposite side of said gears from said passage; air compressing means in the other chamber actuated by the rotation of the driven shaft; and means for controlling the flow of oil through the passage leading from the gear chamber to said air compressing chamber. 30
